UNITED STATES PATENT OFFICE.

FRANÇOIS ROCHEFORT, OF PARIS, FRANCE.

DEVICE FOR INJECTING, PULVERIZING, AND VAPORIZING FUEL IN INTERNAL-COMBUSTION ENGINES.

Application filed April 30, 1923. Serial No. 635,788.

The present invention relates to fuel pulverizing and vaporizing injectors for internal combustion engines, of the type in which the pressure of the liquid fuel itself is utilized for lifting from its seat the fuel injection valve or the like, which likewise forms the valve for the compressed air or compressed gas serving for the diffusion of the liquid fuel, by the pressure of the liquid fuel acting upon a piston connected to, and forming part of said needle valve.

The device in accordance with my invention is characterized by the fact that the liquid fuel is admitted by a passage of very small cross sectional area, between the cylindrical external surface of this needle valve and the cylindrical bore in which the needle valve is displaceable, so as to obtain a constant cross sectional area of passage for the liquid fuel, with a view to ensure its flattening, before its mixture with the diffusing air or other gas under pressure, whatever be the quantity of liquid fuel admitted. The flattening of the liquid fuel is thus maintained whatever be the lift of the piston.

The accompanying drawing represents by way of example one form of construction in accordance with my invention.

Fig. 1 is an axial section of the pulverizing and vaporizing injector, and

Fig. 2 is a transverse section upon the line 2—2 of Fig. 1.

As shown the body of the injector-pulverizer comprises two members *a* and *e* and the member *a* is adapted to be mounted in the cylinder head of the engine and terminates in a conical portion *a'* forming a nozzle and comprises internally a cylindrical bore *a''*.

This member *a* of the body comprises on one side the inlet *d* for the supply of fuel under pressure, and on the other side the inlet *c* for the supply of compressed air. Within the member *a* of the body is located the member *e*, held in place therein by a ring-nut *i* screwed into the member *a*.

This member *e* comprises a conical seat *k'* and below the latter a cylindrical bore *k''*. Within the member *e* is arranged a needle valve, which comprises a cylindrical part *l'*, a conical portion *l*, corresponding to the seat *k'*, and, below this conical portion *l*, is arranged a cylindrical member *m* connected

therewith and forming a piston the external diameter of which corresponds as accurately as possible to the internal diameter of the cylindrical bore *k''* of the member *e*. It is quite obvious that the members *a* and *e* of the body could if desired be made in one piece although it might be quite impractical, the arrangement as shown having for its object merely to facilitate and show a practical manner for the manufacture of the body. Upon the periphery of this member *m* are formed small grooves *m'*, which are sealed by the portion *l* when the latter rests upon its seat *k'*. The needle-valve extends upwards in the form of a stem *l''* provided with guiding ribs *l'''*. This stem is hollowed out internally so as to accomodate a spring *n* which presses at one end upon the bottom of the hollow interior of the needle-valve and at the other end upon a plug *o* which serves at the same time as a stop for the stem *l''* in order to limit rise of the needle-valve.

Fuel is delivered through a port *d'* to beneath the piston *m*; compressed air passes between the ribs *l'''* to above the portion *l* and is held up thereby. An annular groove *k''* is cut in the seat *k'*, to communicate through ports *k''* with grooves *k'''* formed in the conical extremity of the member *e*; which grooves are formed on oblique or helical lines.

The operation of this device is as follows:

Under the pressure of the fuel delivered by the injection pump, the piston *m* is lifted, raising with it the valve, which is lifted from its seat *k'*. The liquid fuel then travels along the grooves *m'*, cut on the external surface of the piston *m* and into the annular groove *k''*, where it mixes with the compressed air, admitted by the valve being lifted from its seat. This mixture flows through the ports *k''* and the grooves *k'''* into the nozzle *a'*, and assumes as a result of the obliquity of the grooves *k'''*, a gyratory motion which produces an intimate mixture of the fluids. The very small quantity of fuel, which may pass by reason of leakages between the piston *m* and the cylindrical bore *k''*, reaches the annular groove *k''* and is carried off by the compressed air, and mixes therewith.

When the injection of fuel ceases, the needle-valve is returned to its seat by the

combined action of the compressed air and of the spring n , or else by the pressure of the compressed air alone if this be sufficient.

Orifices l^s are formed at the lower end of the hollow stem l^s of the needle-valve in order that fuel may never be able to accumulate therein. Orifices l^s formed at the upper part of the stem l^s allow the compressed air always to exert its pressure upon the whole area of the valve l so as to ensure the rapidity of closing of this valve.

What I claim is:

1. In a device for injecting, pulverizing and vaporizing fuel for internal combustion engines, comprising a body, outlet in the body, a needle valve member displaceable in the body, separate inlet means in the body for supplying fuel and gas under pressure to the needle valve member, which is arranged to control the inlet of both fuel and gas under pressure and to open communication between the inlets and the outlet through its displacements relatively to the body, means for moving the needle-valve member relatively to the body through pressure exerted by fuel on the needle-valve member to thus allow inlet of fuel and gas under pressure, and means for moving the needle-valve member in the opposite direction for cutting off the inlet of fuel and gas under pressure, the provision of a piston in the body and forming part of the needle-valve member and arranged to receive the pressure of the liquid fuel under pressure, a cylindrical bore in the body for receiving the piston, the piston having an external diameter corresponding as accurately as possible to the internal diameter of the cylindrical bore in the body, and small through-way grooves between the piston and the cylindrical bore, for permitting discharge of fuel through the body outlet.
2. In a device for injecting, pulverizing and vaporizing fuel for internal combustion engines, comprising a body, outlet in the body, a needle valve member displaceable in the body, separate inlet means in the body for supplying fuel and gas under pressure to the needle valve member, which is arranged to control inlet of both fuel and gas under pressure and to open communication between the inlets and the outlet through its displacements relatively to the body, means for moving the needle-valve member relatively to the body through pressure exerted by fuel on the needle-valve member and thus allow inlet of the fuel and gas under pressure, and means for moving the needle-valve member in the opposite direction for cutting off inlet of fuel and gas under pressure, the provision of a piston in the body forming part of the needle-valve member and arranged to receive the pressure of the liquid fuel under pressure, a cylindrical bore in the body for receiving the piston, the piston having an external diameter corresponding as accurately as possible to the internal diameter of the cylindrical bore in the body, and small through-way grooves between the piston and the cylindrical bore, for permitting discharge of fuel through the body outlet.

In testimony whereof I have signed my name to this specification.

FRANÇOIS ROCHEFORT.
